CLAIM

The ornamental design for a display screen or portion thereof with a set of graphical user interfaces, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with a set of graphical user interfaces showing the claimed design; and,

FIG. 2 is another front view thereof.

The broken lines in the figures show a display screen or portion thereof, and form no part of the claimed design.

The graphical user interface sets of FIGS. 1 and 2 are arranged on the drawing sheets for the convenience of illustration and their relative positioning forms no part of the claimed design.
